ORCHARD HEATER

Percy M. Forster, Berkeley, Calif.

Application September 14, 1937, Serial No. 163,788

3 Claims. (Cl. 158—99)

This invention pertains to orchard heaters of the type employing gas as a fuel.

It is the principal object of the present invention to provide an improved orchard heater utilizing natural or other gas as a fuel, and which is so constructed that the heat is generated efficiently and is distributed in a manner resulting in maximum efficiency in orchard heating.

10 In practicing my invention, I provide an orchard heater of simple construction which may be supported from the ground between the rows of trees, or which may be suspended within the trees. The orchard heater is equipped with a 15 gas burner of novel construction capable of efficient operation either with natural or manufactured gas, or with tank type of gas. The heater is so constructed that the heat generated will be efficiently distributed radially in a manner obtaining maximum efficiency in orchard heating.

One form which the invention may assume is exemplified in the following description and illustrated by way of example in the accompanying drawing, in which:

25 Fig. 1 is a central vertical sectional view through my improved heater, disclosing the preferred form of my invention.

Fig. 2 is a perspective view of the heater.

Fig. 3 is a transverse sectional view through 30 the heater taken on line III—III of Fig. 1.

Fig. 4 is a sectional view taken on line IV—IV of Fig. 1.

Referring more particularly to the accompanying drawing, 10 indicates an orchard heater 35 capable of being supported by legs 11 from the ground between the rows of trees, or which may be suspended within a tree by means of a hook 12. It is obvious that when the device is to be supported within a tree, that the legs 11 may be 40 dispensed with.

The orchard heater 10 is provided with a burner 14 comprising a nozzle body 15 having a hollow cylindrical portion 16, having a closed upper end 17. At the lower end of the cylindrical portion 16 the nozzle body 15 is formed with a hollow frusto-conical portion 18 joined integrally at its inner end with the lower end of the cylindrical portion 16. The larger diameter of the frusto-conical portion 18 is lowermost and 50 is open. Fitting within the frusto-conical portion 18 of the nozzle body 15 is a nozzle member 19 which has an external contour coinciding with the internal contour of the frusto-conical portion 18 so that it will nest therein as illus- 55 trated.

It will be noticed that there is a series of longitudinal grooves formed in the outer surface or periphery of the nozzle member 19 so that gas and air entering the interior of the hollow cylindrical portion 16 of the nozzle body will be directed downwardly and outwardly through these grooves so that a frusto-conical flame will be produced at the outer end of the nozzle.

A tube 20 is provided, the upper end of which is threaded upwardly through the nozzle member 19 so as to communicate at its upper end with the interior of the nozzle body 15 above the nozzle member 19. The other or lower end of the tube is fitted with a venturi 21, centrally into which a fuel nozzle 22 projects. This nozzle 15 22, of course, is connected by means of a pipe 23 with a source of fuel, which may be either natural or manufactured gas, or what is commonly termed tank gas such as butane.

It is obvious, therefore, that by this medium 20 gas and air will be propelled upwardly through the tube 20 into the upper end of the nozzle body 15 and thence will travel downwardly through the grooves in the outer surface of the nozzle member 19, and project in a conical fashion so as to produce a frusto-conical flame at the outer end of the nozzle.

At a spaced distance below the nozzle is a horizontal lower baffle plate 24 which is secured on the tube 20. This plate is preferably circular and disposed coaxially of the tube 20. At the upper end of the nozzle is an upper baffle plate 25 secured to the nozzle itself, as illustrated, by the hook 12 which is threaded into the upper end 17 of the nozzle body member 15.

It will be seen that when the flame from the nozzle is directed downwardly, that the lower baffle will intercept the same and direct it radially outward. The upper baffle will prevent the direct rising of the heat and therefore assist in directing it radially outward.

Arranged concentrically about the nozzle is a radiating screen 26 which is suspended from the nozzle body 15 by a spider 27. It is seen that the outwardly directed flame from the nozzle will heat this screen and prevent the flame from emanating directly outward so as to eliminate fire hazard. This screen, however, will become extremely heated so that the heat will be radiated radially outward therefrom to effect the 50 heating.

In the event that it is desirable to use tank gas or other type of gas requiring preheating, I have provided a heating chamber or coil 28 just underneath the lower baffle plate 24 so it will become 55

heated by radiation and conduction. This heating chamber is in effect a large tube connected at one end to the pipe line 29 leading to the source of gas supply, and at its other end to the tube 23 leading to the fuel nozzle 22. A valve 30 is provided to enable controlling of the gas supply to the fuel nozzle 22.

In operation of the device, it is constructed and assembled as illustrated in the drawing, and if it 10 is to be supported from the ground between the rows of trees, the legs 11 are connected with the lower baffle 24. If the device is to be suspended within a tree, the legs 11 may be dispensed with and the device suspended in proper position by 15 means of the hook 12. The line 29 is then connected with a source of gas supply and the valve 30 is opened to direct the fuel to the fuel nozzle 22. As the fuel is projected into the tube 20, air will be drawn through the lower end of the venturi to co-mingle therewith and pass into the hollow upper portion 16 of the nozzle body 15. It 20 will then project downwardly and outwardly through the grooves in the nozzle member 19 so that it may be ignited at the lower end of the 25 nozzle to produce the flame. This flame will impinge against the lower baffle 24 and heat the same and then will be directed radially outward to heat the surrounding screen 26. As this screen 26 becomes heated, the heat will be radiated therefrom to a large area surrounding the heater. The screen, of course, will tend to confine the flame within it so as to eliminate the possibility of 30 any destruction by the flame.

It will be seen that by directing the gas fuel 35 upwardly that the cold air below the heater will be utilized, and that by directing the flame downwardly and then outwardly, maximum efficiency will be obtained by preventing the direct rise of heat from the burner.

40 If so-called tank gas is used, the same will obviously become preheated due to the provision of the tubular preheating chamber 28 through which the gas will pass prior to reaching the fuel injection nozzle 22.

45 From the foregoing, it is obvious that I have provided a very simple and efficient orchard heater, from which the heat is directed to the area to be heated by radiation rather than by direct flame, and which is provided with a very simple and efficient burner capable of use either with 50 natural, manufactured or tank gas.

While I have shown the preferred form of my invention, it is to be understood that various changes may be made in its construction by those skilled in the art without departing from the spirit 55 of the invention as defined in the appended claims.

Having thus described my invention, what I claim and desire to secure by Letters Patent is:

60 1. A burner including a hollow nozzle having an imperforate upper end, said nozzle having a plurality of circumferentially spaced and downwardly and outwardly extending passageways arranged in a circle about the center of said nozzle and extending through the lower end thereof, a tube disposed coaxially of said nozzle from a point below the same and upwardly through the lower

end thereof, a venturi on the lower end of said tube, and a fuel nozzle located centrally of said venturi whereby fuel and air will be delivered upwardly through said tube into said nozzle whereby the same may discharge downwardly through said 5 passageways, a lower baffle plate arranged parallel to the lower end of said nozzle at a spaced distance below the same and coaxially thereof, the said baffle plate being of a diameter greater than the lower end of said nozzle, and a heat radiating 10 screen member circumscribing the exterior of said lower baffle plate and extending a distance upwardly therefrom.

2. A burner including a hollow nozzle body having an upper imperforate cylindrical portion with 15 a closed upper end, a frusto-conical portion extending from the lower end of said cylindrical portion with its larger diameter lowermost, a nozzle member fitting the interior contour of said frusto-conical portion and having a plurality of 20 longitudinal grooves formed in its outer surface, a tube extending from a point below said nozzle member and upwardly through the same, a venturi on the lower end of said tube, a fuel nozzle at the lower end of said venturi to direct fuel upwardly through said tube, the upper end of said tube communicating with the hollow cylindrical portion of the nozzle body whereby to deliver fuel and air thereto so that the same may discharge 25 downwardly through said grooves, and a lower 30 baffle member arranged parallel to the plane of the lower end of said nozzle member at a spaced distance below the same and of an area greater than the area of the lower end of the nozzle member, and a heat radiating screen circumscribing the 35 periphery of said lower baffle and extending a distance upwardly therefrom.

3. A burner including a hollow nozzle body having an upper imperforate cylindrical portion with 40 a closed upper end, a frusto-conical portion extending from the lower end of said cylindrical portion with its larger diameter lowermost, a nozzle member fitting the interior contour of said frusto-conical portion and having a plurality of 45 longitudinal grooves formed in its outer surface, a tube extending from a point below said nozzle member and upwardly through the same, a venturi on the lower end of said tube, a fuel nozzle at the lower end of said venturi to direct fuel upwardly through said tube, the upper end of said tube communicating with the hollow cylindrical portion of the nozzle body whereby to deliver fuel and air thereto so that the same may discharge 50 downwardly through said grooves, a lower baffle member arranged parallel to the plane of the lower end of said nozzle member at a spaced distance below the same and of an area greater than the area of the lower end of the nozzle member, and a heat radiating screen circumscribing the 55 periphery of said lower baffle and extending a distance upwardly therefrom, an upper baffle arranged parallel to the lower baffle adjacent the upper end of said screen and over the upper end of said nozzle body, the lower baffle, upper baffle, screen and nozzle body being interconnected. 60 65
